UNITED STATES PATENT OFFICE.

FREDERICK J. CLARK, OF BUFFALO, NEW YORK, ASSIGNOR TO EASTMAN MACHINE COMPANY, OF BUFFALO, NEW YORK.

CLOTH-CUTTING MACHINE.

1,051,686.

Specification of Letters Patent. Patented Jan. 28, 1913.

Application filed December 19, 1911. Serial No. 666,681.

To all whom it may concern:

Be it known that I, FREDERICK J. CLARK, a citizen of the United States, residing at Buffalo, in the county of Erie and State of New York, have invented a new and useful Improvement, in Cloth-Cutting Machines, of which the following is a specification.

This invention relates more particularly to improvements in cloth cutting machines of that type in which a driven rotary knife is employed for cutting the cloth, and has especial reference to the sharpening means with which the machine is provided for sharpening the knife.

The object of this invention is to construct a cloth cutting machine of this type having a simple and efficient knife sharpening device which normally stands out of engagement with the knife in a position where it does not interfere with the operator's view of the cutting edge of the knife and the pattern in front of the same; and which can be easily moved into engagement with the knife and will engage the opposite sides of the cutting edge thereof with an equal pressure and will sharpen the same in an even and uniform manner throughout the circumference of the knife; and which is adjustable relative to the knife to conform to changes in the position and size of the knife.

In the accompanying drawing, consisting of two sheets: Figure 1 is a side elevation of a cloth cutting machine provided with a sharpening device embodying the invention.

Fig. 2 is a fragmentary side elevation thereof, on an enlarged scale, showing the sharpening device in engagement with the knife. Fig. 3 is a fragmentary front elevation thereof looking in the direction of the arrow 3 in Fig. 2. Fig. 4 is a longitudinal section through one of the grinding members. Fig.

5 is a fragmentary front elevation of the machine looking in the direction of the arrow 5 in Fig. 2. Fig. 6 is a fragmentary front elevation thereof showing the sharpening device in its raised position. Fig. 7 is a sectional elevation in line 7—7, Fig. 6.

Fig. 8 is a rear elevation of the sharpening device. Fig. 9 is a cross section in line 9—9, Fig. 8. Fig. 10 is a fragmentary side elevation of a cloth cutting machine having a sharpening device of modified construction, showing the same in engagement with the knife. Fig. 11 is a fragmentary front elevation thereof. Fig. 12 is a similar view

showing the sharpening device in its raised position.

Like reference characters refer to like parts in the several figures.

The cloth cutting machine shown is a rotary knife machine of standard type and comprises a base plate A, a standard B secured thereto, a frame C adjustable on the standard, a rotary knife D, the cutting edge of which is beveled on its opposite sides in the usual manner, and a motor E which is carried by the frame and is connected with the knife by suitable driving gears. All of these parts are common in rotary knife machines and may be of any suitable and proper construction.

The present invention relates to the knife sharpening device of the machine, and this, in general terms, consists of two rotary grinding disks or wheels which are supported from the frame of the machine in such a manner that they normally stand at one side of the knife where they do not interfere with the operator's view of the knife and the pattern, but are adapted to be moved in unison into engagement with the opposite sides of the cutting edge of the knife and to bear with equal pressure thereon, thus producing an even and uniform grinding of the knife edge on both sides thereof and preserving the alignment of the edge throughout the circumference of the knife.

In the particular embodiment of the invention shown, F F' represent the grinding disks or wheels, which are of usual construction, comprising a back f to which is secured an annular grinding face or ring f' of emery or other suitable abrasive material, and G G' represent pivotal supporting arms to which the disks F F' may be secured in any suitable manner. As shown, each arm is provided at its outer or free end with an offset portion g through which extends a bolt g' having screwthreaded engagement therewith. The bolt g' is provided at its inner end with a shoulder g² and a reduced end portion g³ upon which is screwed a bushing g⁴ having a reduced bearing portion and an end shoulder. The grinding disk is journaled on the bearing portion of the bushing g⁴ between the end shoulder thereon and a washer g⁵ on the bolt g' which abuts against the shoulder g². By turning the bolt g', the grinding disk can be adjusted axially relative to the offset g of the supporting arm

and a suitable lock nut g^6 may be provided for securing the bolt in its adjusted position on the arm. The supports for the grinding disks are so arranged that when the disks 5 are in engagement with the edge of the knife each disk will be slightly inclined to the vertical plane of the knife, and the grinding face of the disk will be inclined to correspond with the beveled sides of the 10 knife edge. The knife traveling across the engaging face of the disk will produce a rotary motion of the disk but in a direction at an angle to the rotation of the knife so that the engaging face of the disk will 15 effectively grind the edge of the knife.

The arms G G' may be pivotally secured to the frame of the machine and operatively connected together so that they will move in unison in any suitable manner. They 20 may also be made adjustable relative to the frame and knife, if desired. In the present construction they are both pivoted to a supporting member which is adjustably secured to the frame and a uniform adjustment of 25 both arms can thus be effected. This construction comprises a bracket h which is secured to the front of the frame C above the knife and supports a stationary plate H (Figs. 7 and 8) formed integrally therewith 30 and provided with parallel slots h' h'' . An adjustable plate I is secured to the front face of the plate H by a screwthreaded bolt i (Figs. 8 and 9) which extends through the slot h' and has screwthreaded engagement 35 with the plate I . The stationary plate H has a guide channel i' in the outer face thereof and the adjusting plate I has a rib i'' (Fig. 3) which engages therein for guiding the adjusting plate in its movements on 40 the stationary plate. For effecting this adjustment of the plate I , it is provided with a lateral ear or lug k in which is mounted an adjusting screw K which engages an ear k' on the bracket h . A uniform adjustment of 45 the disk carrying arm can thus be easily effected, but any other suitable means for adjustably connecting the disk and carrying arms to the frame may be employed if desired.

50 The disk carrying arms are pivotally secured to the adjusting plate I as follows: The arm G is provided with a pivot pin or bolt L which is journaled in an opening in the plate I and extends through the slot h'' 55 in the plate H and through an opening in the end of the arm G with which it has screwthreaded engagement. The bolt L has a shoulder l and is provided, between this shoulder and the inner face of the arm G , 60 with a spacing sleeve l' . The outer end of this bolt has a nut l'' which engages the outer face of the arm G , and the arm can thus be rigidly secured to the bolt. The arm G' is secured to the plate I by a bolt M 65 which has screwthreaded engagement with

the plate I at its inner end and is provided with an annular flange or stop m between which and the face of the plate I there is journaled a gear sleeve m' to which one end of the arm is secured so that the sleeve and 70 arm turn together.

The disk carrying arms G and G' are operatively connected together in the construction shown in a very simple manner. The pivot L to which the arm G is secured 75 has an enlarged toothed head N which meshes with the teeth of the gear sleeve m' to which the arm G' is secured. The two arms will thus always move in unison in opposite directions and any force applied to 80 either arm will be at once directly communicated to the other arm.

The pivoted arms G G' are normally held in a raised position above the knife by a spring O which is secured to a projecting 85 end of the bolt M and engages the outer end of the arm G' , but any other suitable means may be employed for this purpose. The shape and arrangement of the disk carrying arms are such that in their raised 90 position they extend at one side of the vertical plane of the knife where they and the grinding disks carried by them do not interfere with the operator's view of the knife and the pattern.

95 P represents a handle which is secured to the arm G to facilitate the swinging of the arms into their lowered position in which their grinding disks are in engagement with the knife, and the retaining of them in this position until the knife has been sharpened. Any force which is applied to the arm G 100 during the sharpening operation will be communicated to the arm G' so that the grinding disks F and F' will bear with 105 equal pressure against the opposite beveled sides of the cutting edge and grind the same uniformly on both sides. The grinding disks or wheels are separately adjustable 110 on their supporting arms relative to each other and to the sides of the knife which they engage, and the two disk carrying arms are adjustable together relative to the frame and the knife. This enables the device to be readily and carefully adjusted so that both 115 grinding wheels will be in position for proper engagement with the cutting edge of the knife and will simultaneously engage the same and bear thereon with equal force. These adjustments are ample to take care 120 of any change in the size or position of the knife due to wear or any adjustment of the knife. The disk carrying arms being both pivoted to the same supporting plate, their 125 engaging gears will always remain in mesh irrespective of any adjustment of their support relative to the frame of the machine.

In Figs. 10, 11 and 12 is shown a modified construction in which sharpening wheels R R' having peripheral sharpening surfaces r 130

are employed in the place of the sharpening disks F F'. These wheels are mounted upon pivoted arms S S' which are adjustably secured to the frame of the machine and operatively connected together to swing in unison and normally held in a raised position above the knife, in the same manner as the arms G G' above described. The wheels R R' are so arranged on the arms S S' that when the wheels are in engagement with the knife, their axes extend substantially parallel with the vertical plane of the knife at opposite sides thereof so that the periphery of the wheels will engage the opposite sides 5 of the beveled edge of the knife. In this construction, as in the other, the grinding wheels bear equally against the opposite sides of the cutting edge and grind the same evenly and uniformly throughout its length.

10 In both constructions the sharpening device is of simple and compact construction, can be readily secured to the frame of the machine and easily operated for sharpening the knife. The simultaneous engagement of 15 the grinding wheels or disks with the opposite sides of the cutting edge of the knife enables the knife edge to be quickly ground and produces a sharp and uniform cutting edge throughout the entire circumference 20 of the knife. The grinding members can be quickly adjusted so that they will equally engage the opposite sides of the knife and can be raised or lowered relative to the knife to bring them to a proper position for engaging the opposite beveled sides thereof.

I claim as my invention:

1. In a cloth cutting machine, the combination with a rotary knife, of a sharpening device therefor comprising opposed 40 grinding members which are movably mounted on the frame of the machine and are adapted to be moved into and out of sharpening engagement with the knife, and connections between said members which operate, when either member is moved in either 45 direction, to positively produce a simultaneous opposite movement of the other member, substantially as set forth.

2. In a cloth cutting machine, the combination with a rotary knife, of a sharpening device therefor comprising opposed grinding members which are pivotally mounted on the frame of the machine to swing thereon in opposite directions into and 55 out of engagement with the opposite sides of the cutting edge of the knife, and connections between said members which operate, when either member is moved into or out of engagement with one side of said 60 cutting edge, to positively and simultaneously move the other member likewise into or out of engagement with the opposite side of said cutting edge, substantially as set forth.

3. In a cloth cutting machine, the com-

bination with a rotary knife, of a sharpening device therefor comprising opposed grinding members, supports for said members which are pivotally mounted on the frame of the machine to swing thereon in opposite directions, and connections between said supports which operate, when either member is moved in either direction, to produce a positive and simultaneous movement of the other member in an opposite direction, substantially as set forth.

4. In a cloth cutting machine, the combination with a rotary knife, of a sharpening device therefor comprising opposed grinding members, supports for said members which are pivotally mounted on the frame of the machine to swing thereon in opposite directions to move said members into and out of engagement with the opposite sides of the sharpening edge of the knife, 80 connections between said members which operate, when either member is moved into or out of engagement with one side of said cutting edge, to likewise positively move the other member into or out of engagement 85 with the opposite side thereof, and means connected with one of said members for moving said members into and out of engagement with said cutting edge, substantially as set forth.

5. In a cloth cutting machine, the combination with a rotary knife, of a sharpening device therefor comprising opposed grinding members, supporting arms for said members which are movable in opposite 100 directions to bring said members into and out of sharpening engagement with the knife, connections between said arms which operate to produce a simultaneous opposite movement of said arms when either arm is moved, and a support for said arms which is adjustably secured to the frame of the machine, substantially as set forth.

6. In a cloth cutting machine, the combination with a rotary knife, of a sharpening device therefor comprising opposed grinding members, supports for said members which are movably mounted on the frame of the machine and are movable thereon to a position in which said members have sharpening engagement with said knife, and to a position in which said members stand above and at one side of said knife, and means for normally retaining said supports in said last mentioned position, substantially as set forth.

7. In a cloth cutting machine, the combination with a rotary knife, of a sharpening device therefor comprising opposed grinding members, supports for said members which are pivotally mounted on the frame of the machine to swing thereon in opposite directions to move said members into and out of engagement with the opposite sides of the sharpening edge of the

knife, said members being adjustable on said supports relative to each other and to the cutting edge of the knife, and connections between said members which operate 5 when one member is moved in one direction to produce a positive and simultaneous movement of the other member in an opposite direction, substantially as set forth.

8. In a cloth cutting machine, the combination with a rotary knife, of a sharpening device therefor comprising opposed grinding members, separate arms on which said members are journaled, a supporting plate to which said arms are pivoted, means 10 for adjustably securing said plate to the frame of the machine, means for normally 15

retaining said arms in a raised position with their grinding members out of engagement with the knife and at one side of the vertical plane thereof, and connections between said arms which produce a uniform movement thereof in opposite directions to bring said grinding members into engagement with the opposite sides of the cutting edge of the knife, substantially as set forth. 20 25

Witness my hand, this 15th day of December, 1911.
